UNITED STATES PATENT OFFICE.

EBENEZER A. W. JEFFERIES, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GAS-PRODUCER.

1,085,686.

Specification of Letters Patent. Patented Feb. 3, 1914.

Application filed March 9, 1910. Serial No. 548,172.

To all whom it may concern:

Be it known that I, EBENEZER A. W. JEFFERIES, a citizen of the United States, residing at Worcester, in the county of Worcester and Commonwealth of Massachusetts, have invented a new and useful Improvement in Gas-Producers, of which the following is a specification, accompanied by a drawing forming a part of the same and representing 10 a side elevation of a gas-producer, shown in central vertical sectional view and embodying my present invention.

Referring to the accompanying drawing, 1 denotes a gas producing chamber and 2 an ash pan spaced below the lower end of the gas producing chamber. Mounted upon the bottom of the ash pan is a central air chamber 3 to which air under pressure is supplied through a supply pipe 4. Through 20 openings in the top of the chamber 3 a blast of air is delivered to the interior of the gas producing chamber in order to support combustion. Fuel is fed to the upper end of the gas producing chamber from a hopper 5.

25 The above mentioned parts of the apparatus form no part of my present invention and may be of any known and usual form of construction.

The lower portion of the casing surrounding the gas producing chamber consists, 30 preferably, of a metallic wall 6 surrounded by an annular chamber 7 which is supplied with water in order to prevent the undue heating of the metallic wall 6. In the present instance water is supplied to the annular chamber 7 by an overflow pipe 8 leading from a water chamber 9 formed on the cover of the gas producer for the purpose of water sealing the fuel feeding mechanism. The 35 annular chamber 7 is also provided with an overflow pipe 10.

Inclosed within the annular chamber 7 is a coil of pipe 11 communicating at one end, 40 through a pipe 12 with a source of water supply and at the opposite end, in the present instance, through a pipe 13 with a pipe 14 passing diametrically through the gas producing chamber 1. The pipe 14 is connected with a pipe 15 which enters the air supply pipe 4 and communicates with a vertical pipe 16 through which water, heated by its passage through the coil 11 and pipe 14, is delivered into the air chamber 3 through nozzles 17, 18 and 19 at the top of 45 the vertical pipe 16. The delivery through

the nozzles is, preferably, in the form of a spray which facilitates a thorough admixture of water with the air passing into the gas producing chamber through the supply pipe 4. The water passing vertically upward through the nozzle 19 strikes a cap or baffle-plate 20 and, that portion which falls by gravity, is received upon a conical shield plate 21 from the edge of which water falls downward meeting the upward current of air which is supplied from any suitable source of air supply under pressure such, for example, as a pressure blower, or other means now employed for forcing an air blast into the gas producing chamber.

In the construction of a gas producer, as shown in the present drawing, the air chamber 3 communicates with chambers inclosed by the radiating arms 22, 22 and the nozzles 17 and 18 are directed toward the chambers inclosed by these arms so that the spray of water will be delivered into each of the chambers, that lodging in the chambers being converted into steam and carried out into the gas producing chamber by the air blast, through slots 23.

It has been customary heretofore to admit a mingled current of air and steam through the supply pipe 4 to the gas producing chamber, the steam being admitted under pressure in the form of a jet, the force of which served to induce an air current which, mingling with the steam, was admitted to the gas producing chamber to support combustion. By my present improvement I 85 force a current of air under pressure through the pipe 4, and supply the requisite moisture by vaporizing the water admitted to the air chamber 3, preferably in the form of a spray, the water supply having been 90 preheated by heat generated in the gas producing chamber.

I do not confine myself to the specific construction shown and described for the purpose of imparting heat to the water supply, 100 but I have shown what I deem to be a preferable and convenient method of imparting heat to the water supply by conducting the water through the coil of pipe 11, preferably of copper, submerged in the water contained in the annular water chamber 7, which becomes heated by heat generated within the gas producing chamber and conducted through a common metallic wall 6. I thereby avoid the extra cost involved in the

converting the water into steam by the method now commonly practised, and also I am able to regulate the amount of moisture taken up by the air supply. As the vaporization takes place within the inclosed air spaces within the gas producing chamber, I am able to reduce their temperature and protect them from the injury arising from excessive heating. The movement of the water supply through the coil 11 tends to reduce the temperature of the water in the annular water chamber 7, rendering it more efficient in maintaining a low temperature in the wall 6 of the gas producing chamber.

I claim,

1. In a gas producer, the combination with a gas producing chamber, of a water cooler for a part of said chamber, an air inlet pipe for the admission of air to said chamber, and a water pipe leading from a source of water supply to said inlet pipe and inclosed within said water cooler, whereby the water in said water pipe is heated by the heat of the water in said water cooler.

2. In a gas producer, the combination with a gas producing chamber, of a water cooler for a part of said chamber, an air inlet pipe for the admission of air to said chamber, and a water pipe leading from a source of water supply to said inlet pipe and passing through said water cooler.

3. In a gas producer, the combination with a gas producing chamber, of a water cooler for a part of said chamber, an air inlet pipe for the admission of air to said chamber, and a water pipe passing through

said water cooler and through the fire in said chamber and discharging into said inlet pipe.

4. In a gas producer, a gas producing chamber, an air inlet pipe to said chamber, an annular water chamber surrounding said gas producing chamber having a common dividing wall, a coil of pipe inclosed in said water chamber, a pipe leading from one end of said coil to a source of water supply, and a pipe leading from the opposite end of said coil to the interior of said air inlet pipe.

5. In a gas producer, a gas producing chamber, an inclosed air chamber, an air supply pipe leading to said air chamber, hollow arms extending laterally from said air chamber into said gas producing chamber and having openings for the delivery of air thereto, means for supplying water to the interior of said hollow arms, and means for preheating the water supply by heat generated in the gas producing chamber.

6. In a gas producer, the combination with a gas producing chamber, of an air chamber inclosed in said gas producing chamber, means for supplying air under pressure to said air chamber, hollow arms communicating with said air chamber and extending into said gas producing chamber and having openings thereto, and means for supplying preheated water in the form of a spray to said air chamber.

Dated this third day of March 1910.
EBENEZER A. W. JEFFERIES.
